UNITED STATES PATENT OFFICE.

JOSEPH SALOMON, OF CHICAGO, ILLINOIS, ASSIGNOR TO ROYAL METAL MANUFACTURING COMPANY, OF CHICAGO, ILLINOIS, A CORPORATION OF ILLINOIS.

DESIGN FOR A SIDE STANDARD OF OPERA-CHAIRS.

No. 39,711.

Specification for Design.

Patented Dec. 22, 1908.

Application filed July 6, 1908. Serial No. 442,256. Term of patent 7 years.

To all whom it may concern:

Be it known that I, JOSEPH SALOMON, a citizen of the United States, residing at Chicago, in the county of Cook and State of Illinois, have invented a new, original, and ornamental Design for Side Standards for Opera-Chairs, of which the following is a specification, reference being had to the accompanying drawing, forming part thereof.

The figure is a perspective view of a side

standard for opera-chairs, showing my new design.

I claim:

The ornamental design for the side standard of an opera-chair, as shown.

JOSEPH SALOMON.
